UNITED STATES PATENT OFFICE.

FRANK L. WRIGHT, OF CHICAGO, ILLINOIS, ASSIGNOR TO THE LUXFER PRISM PATENTS COMPANY, OF SAME PLACE.

DESIGN FOR A PRISM-PLATE AND BORDER.

SPECIFICATION forming part of Design No. 28,017, dated December 7, 1897.

Application filed October 13, 1897. Serial No. 655,083. Term of patent 14 years.

To all whom it may concern:

Be it known that I, FRANK L. WRIGHT, a citizen of the United States, residing at Chicago, in the county of Cook and State of Illinois, have invented a certain new and original Design for a Prism-Plate and Border, of which the following is a description.

My invention relates to designs for prism-plates and borders.

Figure 1 is an elevation of a plate of my design. Fig. 2 is a vertical section.

A is a prism-plate with prisms B on one side and a surrounding border C.

I have illustrated the border as open-work. The essential features of my design are 15 found in a prism-plate with a surrounding border lying in substantially the same plane as the body of the prism-plate.

I claim--

A design for a prism-plate and border, substantially as shown and described.

FRANK L. WRIGHT.
